UNITED STATES PATENT OFFICE.

DANIEL S. REGAN, OF SAN FRANCISCO, CALIFORNIA, ASSIGNOR TO THE
REGAN VAPOR ENGINE COMPANY, OF SAME PLACE.

VAPOR-ENGINE.

SPECIFICATION forming part of Letters Patent No. 448,369, dated March 17, 1891.

Application filed November 6, 1890. Serial No. 370,445. (No model.)

To all whom it may concern:

Be it known that I, DANIEL S. REGAN, a citizen of the United States, residing in San Francisco, in the county of San Francisco and State of California, have invented a new and useful Improvement in Vapor-Engines, of which the following is a specification.

My invention relates to improvements in vapor or gas engines.

- 10 Vapor or gas engines heretofore in use have usually been so constructed as to exert one power-stroke to every four-strokes of the piston, the first stroke of the piston, for example, serving to draw in the charge of gas and air, the second stroke to compress and ignite the charge, the third stroke being the power-stroke, and the fourth stroke to exhaust the cylinder preparatory to receiving a new charge. One objection or disadvantage in 15 the practical use of such engines has been lack of efficiency or economy in fuel, owing to the fact that the cylinder exhausts at a high pressure, thus occasioning considerable loss of power, and another the want of steadiness or regularity in the motion of the engine, owing to the fact that the piston exerts power in only one stroke out of four, while at its other three strokes, and especially at the charge-compressing stroke, it consumes power.
- 20 Owing to this one-in-four intermediate action of the piston in exerting power upon the crank-shaft of these engines it has heretofore been necessary to employ heavy fly-wheels.
- 25 The object of my invention is to overcome these difficulties and to provide a gas or vapor engine of a simple and durable construction which will operate efficiently and economically and without the necessity of employing heavy fly-wheels.

- 30 It consists in the novel construction of the cylinders and other parts and in the novel combinations of parts and devices herein shown and described, and more particularly pointed out in the claims.

- 35 In the accompanying drawings, which form a part of this specification, and in which similar letters of reference indicate like parts throughout all the figures, Figure 1 is a side elevation of an engine embodying my invention, the same showing the valve-chamber in vertical section. Fig. 2 is a vertical section

taken on line 2 2 of Fig. 1. Fig. 3 is a central vertical section through the three cylinders, the same being taken on line 3 3 of Fig. 2. Fig. 4 is a detail sectional view of the exhaust 55 port or valve.

In the drawings, A represents the frame of the machine or engine, the same being of any suitable form or construction.

B and B' are the two high-pressure cylinders, and B² the intermediate low-pressure cylinder.

C, C', and C² are the pistons of the several cylinders, connected by pitman-rods c with the main driving-shaft or crank-shaft C³ of the 65 engine. The cylinders B, B', and B² are preferably all cast in one piece and are provided with water-jacket chambers b, surrounding the same. The cylinder-casting may also, preferably, be made integral with the frame A. 70

D and D' are the igniting-chambers for the high-pressure cylinders B and B', the same being secured to the cylinders by bolts d, extending through suitable flanges on the castings. Caps D², bolted to the igniting-chamber 75 casting D' D', close the igniting-chambers. These caps are most conveniently made separate from the igniting-chamber casting D' D', and, being removable, they afford ready access to the igniting-chamber when necessary to adjust, replace, or repair the electrodes.

E represents an electric battery or source of electric energy, and F the electric circuit.

f and f' are the electrodes or contact-pieces in the igniting-chamber D or D'. One of 85 these electrodes is insulated from the machine; the other of course need not be. One of these electrodes is preferably a spring; the other, of course, need not be. One of these two electrodes is moved or operated to make 90 contact with the other by the piston or by some moving part connected therewith. The most convenient way to operate the movable electrode f is to attach it directly to the piston, as no intermediate mechanism is thus required to communicate motion to it from the piston. I prefer to insulate the stationary electrode f'. Insulation is indicated at f². I prefer to make the stationary electrode f' the spring one and to attach it to a removable 100 binding post or holder f³. One pole of the electric battery connects with the insulated

contact-piece or electrode f' , the other with the movable electrode f through the metal work of the engine which forms part of the circuit. The electric circuit F is alternately closed through the electrodes $f f'$ in the igniting-chamber D, and the similar electrodes in the igniting-chamber D' by means of a pair of movable contact-pieces $f^4 f^5$, which alternately make connection with a stationary contact-piece f^6 , which forms part of the electric circuit.

G is the valve box or chamber. It is divided into three compartments g , g' , and g^2 by partitions or webs G' . It is also furnished with a number of water-compartments g^3 to keep the same cool. The valve-box is furnished with four puppet-valves H H' and K K', which close the ports $h h'$ and $k k'$. The compartments or passages g and g' communicate through the valve-ports h and k with the ports g^4 and g^5 , leading, respectively, to the two high-pressure cylinders B and B', and the compartment g^2 communicates through the port or passage g^6 with the low-pressure cylinder B². By thus providing two valves, as H and H', between each high-pressure cylinder and the low-pressure cylinder one of the valves H closes the high-pressure cylinder during the explosive or power stroke of its piston, while the other valve H' closes the communication between the low-pressure and said first-mentioned high-pressure cylinder, while the other high-pressure cylinder is exhausting into the low-pressure cylinder. By this arrangement the pressure of the puppet-valves serves to hold them closed at the proper times. The valves H and H' are automatically raised or opened by a pitman H², operated by a crank m on the valve-operating shaft M. The valves K and K' are operated by a similar pitman K², actuated by a crank m' on the shaft M. Springs H³ K³ hold the valves H H' and K K' normally seated.

N represents the inlet-port into each of the igniting-chambers D D', and N' the puppet-valve for closing the same.

P represents the exhaust port or valve leading from the low-pressure cylinder B², and P' the puppet-valve for closing the same. I find by experience that an ordinary puppet-valve may be satisfactorily used for closing this exhaust-port, as the exhaust-port may be comparatively small, and as the loss through this small port during the power-stroke of the piston C² will not be considerable, owing to the rapid movement of the piston C² and the large size of the cylinder B². The cylinder B² should be made of double the size of the cylinders B B—that is to say, the area of the piston C² is twice the area of the piston C or C'.

The operation is as follows: On the first or down stroke, for example, of the piston C, the high-pressure cylinder B draws in a charge of commingled air and gas through the supply-port N. At the second or back stroke of the piston C this charge is compressed, and as this second stroke is finished

the charge is ignited by the contact and subsequent separation of the electrodes $f f'$ in the igniting-chamber D. The piston C then makes its third or explosive stroke, thus exerting power upon the crank C³. The valve-operating shaft M then lifts or opens the valves H H', and as the piston C makes its fourth or return stroke, completing its cycle, the exhaust passes out through the valve H and under the valve H' and through the passage or compartment g^2 into the low-pressure cylinder B², the exhaust-pressure at this time holding the opposite valve K' closed. The piston C² of the cylinder B² being of twice the area of the piston C, thus exerts power upon the crank-shaft C³, corresponding to the difference in area of the pistons C² and C. Upon the return-stroke of the piston C² the exhaust, now at a low pressure, escapes through the exhaust-port P and into the outer air. At the fourth or exhaust-expelling stroke of the piston C, though the electrodes $f f'$ are of course brought into contact by the piston, no electric spark is produced by the contact or separation of the electrodes at this fourth stroke, because at this time the circuit is not closed at $f^4 f^6$. The spark of course is only produced in the igniting-chamber of the cylinder B when the circuit is simultaneously closed at both the points where it is open—that is to say, at the contacts $f f'$ and $f^4 f^6$. This only takes place at the end or finish of the second or charge-compressing stroke of the piston C. The circuit is thus only momentarily closed and at the time the spark is needed to ignite the charge. In the meanwhile the alternately-acting high-pressure cylinder B' has gone through the same operations as the first mentioned high-pressure cylinder B, but alternately therewith, so that one of the three pistons is exerting power upon the crank-shaft at all times—that is to say, first one of the high-pressure cylinders, then the low-pressure, then the other high pressure, and then the low pressure, and so on continuously. In like manner the spark is only produced in the igniting-chamber of the cylinder B' when the circuit is simultaneously closed at the two openings or breaks $f f'$ and $f^5 f^6$. As the shaft M, which operates the circuit-closing devices $f^4 f^5$, revolves at only half the speed of the crank-shaft C, the circuit will only be closed at $f^4 f^6$ —for example, when the piston C is making or finishing its second stroke and not the fourth stroke of said piston C, and so in like manner the circuit will only be closed at $f^5 f^6$ at the corresponding charge-compressing stroke of the other piston C'.

The valve-operating shaft M is driven from the main driving-shaft C³ at half the speed of the driving-shaft, so that the valves and the circuit-closing devices $f^4 f^6$ will be operated in proper time.

$m^2 m^3$ represent the gears for communicating motion from the driving-shaft C³ to the valve-operating shaft M.

I claim—

1. In a gas or vapor engine, the combination, with two alternately-acting high-pressure cylinders, each having a piston and furnished with an igniting-chamber, a single low-pressure cylinder having a piston and taking the exhaust alternately from each of said high-pressure cylinders, a single electric battery and normally-open circuit having normally-separated electrodes or contact-points in each of said igniting-chambers, one of said electrodes in each of said igniting-chambers of said cylinders being movable and carried on or operated by the piston to close the circuit and produce the igniting-spark at the end of its charge-compressing stroke, said circuit being also provided with a circuit closer and breaker device at another point to close the circuit alternately through the electrodes of each of said igniting-chambers, the one electric battery and circuit serving to explode the charges in the igniting-chambers of both cylinders, substantially as specified.
2. In a gas or vapor engine, the combination, with two alternately-acting high-pressure cylinders, each having pistons and furnished with an igniting-chamber, two normally-separated electrodes in each of said igniting-chambers, one of said electrodes in each chamber being a spring and one in each chamber being movable and carried on or operated by the piston, a single electric battery and circuit having two branches, one branch leading to each igniting-chamber, and a circuit closing and breaking device operating to alternately close the circuit through each of said branches to alternately explode the charges in the igniting-chambers of both cylinders, substantially as specified.
3. In a gas or vapor engine, the combination, with two alternately-acting high pressure cylinders B B', each furnished with an

igniting-chamber having a stationary insulated spring-electrode f' therein, pistons C C', each furnished with an electrode f , an electric battery E and circuit F, having two branches, one leading to each of said insulating-electrodes f' in said igniting-chambers, and a circuit closing and breaking device $f^4 f^5 f^6$, operating to alternately close the circuit through each of said branches leading to the igniting-chambers, whereby the circuit is closed and the spark produced in each of said igniting-chambers only at the end of the charge-compressing stroke of each piston, substantially as specified.

4. The combination, in a gas or vapor engine, of two alternately-acting high-pressure cylinders, each having a piston and furnished with an igniting-chamber, of a low-pressure cylinder having a piston and taking the exhaust alternately from each of the two high-pressure cylinders, a common crank-shaft, to which the pistons of all three of said cylinders are connected, a valve-box G, divided into three compartments $g' g^2$ and provided with ports and four puppet-valves H H' K K' for opening and closing the communication between said cylinders, a valve-operating shaft M, having pitmen $H^2 K^2$ for alternately operating said valves H H' and K K', a single electric battery and circuit, normally-separated electrodes $f' f'$ in each of said igniting-chambers, said circuit having separate branches leading to said electrodes $f' f'$, and a circuit closing and breaking device $f^4 f^5 f^6$, connected to and operated by said valve-shaft M, to close the circuit alternately through each of said branches, substantially as specified.
